UNITED STATES PATENT OFFICE.

EDWARD HASTI, OF ST. PAUL, MINNESOTA.

VARIABLE-POWER DRIVE.

1,247,530.

Specification of Letters Patent. Patented Nov. 20, 1917.

Application filed November 27, 1916. Serial No. 133,782.

To all whom it may concern:

Be it known that I, EDWARD HASTI, a citizen of the United States, and a resident of St. Paul, in the county of Ramsey and State 5 of Minnesota, have invented certain new and useful Improvements in Variable-Power Drives, of which the following is a specification.

One object of my invention is to provide 10 means for varying the power ratio in a power drive.

Another object of my invention is to provide in a driving member having wedge members thereon, means for varying the 15 angle of application of the wedge member.

Another object of my invention is to provide a power wheel having wedge members thereon, and means for applying the wedge members to the thread of a worm that is cut 20 or laid by the wedge members themselves.

With these and incidental objects in view, 25 the invention consists of certain novel features of construction and combination of parts, the essential elements of which are hereinafter described with reference to the drawing which accompanies and forms a part of this specification.

Figure 1 is a plan view partly in section of 30 an ice boat to which my improved variable power drive is applied.

Fig. 2 is a side elevation of the same boat. Fig. 3 is a side elevation of my variable power drive applied to a speed boat, and Fig. 4 is an enlarged sectional view of a 35 modification of one of the power wheels.

The body 1, Fig. 1, of the ice boat to which my variable power drive is applied, has suitably mounted thereon an internal combustion engine 2, or any suitable source of 40 power.

Driven through the bevel gear transmission 3 by shafts 4 and 5 are two power wheels 6 and 7, respectively.

The shaft 5 is connected by a universal 45 joint 8 to the shaft 9 driven directly by the bevel gear 10 to bring the drive of the wheel 7 in the same horizontal plane as that of the wheel 6.

The wheels 6 and 7 are driven forwardly, 50 and when starting the wedge members 11 give traction to the wheels and serve to propel the boat forward in the direction shown by the arrow 12, although it will be understood that the wedge members 11 will cut 55 and break up the ice on account of the angular position of the wheels 6 and 7.

As the boat gets under way, and hence there is less power required to keep it in motion, the wedge members 11 will act in an entirely different manner, which can 60 best be illustrated by reference to the well known action of a worm and worm gear.

When the boat is under way, the wheels 6 and 7 are to be considered as worm gears, meshing with portions of worm threads, 65 which are actually cut into the surface of the ice on which the boat rides, by the wedge members 11.

When a wedge member 11 has cut its individual thread in the ice, and the wheel is 70 still turning in a forward direction, a pressure will be exerted between the wedge member 11 and the side of the worm thread cut in the ice, and as the coefficient of friction between the steel wedge members and 75 the ice is extremely low, the wedge members will slide in the ice instead of breaking their way out as they did in starting.

This causes the wheels 6 and 7, which are still to be considered as worm gears to travel 80 along the worm threads cut in the ice, and as the worm, which is the ice itself, cannot turn, these wedge members will slide forwardly as the wheels revolve.

As the angle of inclination of the wedge 85 members to the center line of the boat may be varied, it is readily seen that when the boat is under way on a surface having practically no friction, the boat will be propelled forward at a high rate of speed with a low 90 rate of revolution speed of the wheels 6 and 7.

The shafts 10 and 4, Fig. 1, are supported by brackets 13 and 14, respectively, which are carried by the king bolt 15. 95

The bearings 16 held in place by suitable collars 17 pinned to the shafts, carry by hinged connections the links 18, which in turn are hinged to the member 19, which is 100 slidably mounted on the guide rod 20.

By sliding the member 19 forward or backward on the bar 20, it is evident that the angular position of the wheels 6 and 7, and also the angular position of the wedge members 11 carried thereon, may be varied, 105 and the speed of the boat thus varied without increasing or decreasing the speed at which the wheels 6 and 7 turn.

Fig. 3 shows the power drive as applied to a motor boat, and as the coefficient of 110 friction between water and the plates 21 will be very slight, it is evident that a simi-

lar result will be obtained in water as upon ice, and in either of the applications, the speed may be regulated by positioning the member 19, which can be locked in any desired position by setting the lever 22 in the quadrant 23 at any desired position, the link 24 which is hinged to the lever 22 and the member 19 controlling the position of the member 19.

10 In Fig. 4 I show means for adjusting the angular position of the wedge members 11 without changing the angular position of the wheel.

15 In this construction I prefer to have the spokes 25 slidably mounted in the hub 26 and utilize a spring 27 re-acting between the rim 28 and the collar 29 to maintain the tension of the wedge member 11 against the rim 28.

20 Journaled on the hub 26 is a ring 30 to which is hinged at 31 projections 32 carried by the spokes 25. The support 33 journaled on the shaft 4 between the collar 34 and the hub 26 has hinged thereon a bell 25 crank 35 controlled by a suitable link 36, and hinged at the other end to the ring 30.

It is evident from the drawing that a movement of the lever 36 will slide the ring 30 in or out from the spokes, and as the projections 32 are normally set at an angle, preferably of 45 degrees to the shaft 4, the motion of the ring 30 will turn the wedge members angularly on the rim 28 of the wheel.

35 Claims:

1. In a variable power drive the combination of a rotating member mounted for rotation on an axis positionable at an acute angle with the direction of the line of the forward motion of the object to which the power drive is applied, wedge members carried on said rotating member and adapted

to travel over a substantially flat surface to which the device is applied, and means for varying the angular position of said wedge members with respect to the line of the forward motion of the object to which the power drive is applied. 45

2. In a variable power drive the combination of a drive wheel mounted for rotation on an axis positioned at an acute angle with the line of the forward motion of the device to which the drive is applied, wedge members carried by said drive wheel, means for varying the angular position of said wedge members with respect to the axis of said wheel, and means for mounting said power drive onto an anti-friction supported vehicle. 50 55

3. In a variable power drive the combination with a movable vehicle of a prime mover, a rotatable member adapted to be driven by said prime mover and rotated in a plane at an angle with the plane perpendicular to the longitudinal axis of the vehicle, wedge members on said drive member serving as teeth of a worm gear and adapted to cut the thread of a worm in the surface on which said vehicle travels so that said wedge members co-act with said thread. 60 65

4. In a variable power drive the combination with a movable vehicle of a prime mover, a rotatable drive member adapted to be driven by said prime mover and rotated in a plane at an angle with the plane perpendicular to the longitudinal axis of the vehicle, wedge members on said drive member serving as teeth of a worm gear and adapted to cut the thread of a worm in the surface on which said vehicle travels so that said wedge members co-act with said thread, and means for varying the angularity of said wedge members with respect to the longitudinal axis of the vehicle. 70 75 80

EDWARD HASTI.
